The ornamental design for a solar cell package design, as shown and described.

DESCRIPTION

FIG. 1 is a top perspective view of a solar cell package design showing our new design;

FIG. 2 is a front side view thereof;

FIG. 3 is a top plan view thereof;

FIG. 4 is a left side view thereof;

FIG. 5 is a right side view thereof;

FIG. 6 is a rear view thereof;

FIG. 7 is a bottom plan view thereof;

FIG. 8 is a top perspective view of an alternative embodiment thereof;

FIG. 9 is a front side view thereof;

FIG. 10 is a top plan view thereof;

FIG. 11 is a left side view thereof;

FIG. 12 is a right side view thereof;

FIG. 13 is a rear side view thereof; and,

FIG. 14 is a bottom plan view thereof.

The broken lines shown are for illustrative purposes and form no part of the claimed design.
